UNITED STATES PATENT OFFICE.

LOUIS JAKUBEC, OF SALEM, OREGON.

CAN-OPENER.

1,280,746.

Specification of Letters Patent. Patented Oct. 8, 1918.

Application filed February 25, 1918. Serial No. 219,033.

To all whom it may concern:

Be it known that I, LOUIS JAKUBEC, a subject of the Emperor of Austria, (having declared my intention to become a citizen 5 of the United States of America,) residing at Salem, in the county of Marion and State of Oregon, have invented certain new and useful Improvements in Can-Openers, of which the following is a specification.

10 This invention relates to certain new and useful improvements in can openers.

The primary object of the invention is the provision of a device for making circular cuts in sheet metal such as tin and so arranged 15 that circles of different diameters may be cut by the device, the same being suitable in construction and easy and inexpensive to manufacture.

A further object of the invention is the 20 provision of a hand implement arranged with adjustable means for cutting circular openings of different diameters in the ends of tin cans for gaining access to the interior of the can, the device possessing great 25 strength and durability.

In the drawings forming a part of this application and in which like reference characters refer to corresponding parts throughout the several views,

30 Figure 1 is a central longitudinal sectional view taken through the device with the handle broken away and the pivot member illustrated by dotted lines in its adjusted position.

35 Fig. 2 is a side elevational view thereof. Figs. 3, 4, 5 and 6 are transverse sectional views of the same taken upon lines III—III, IV—IV, V—V and VI—VI, respectively of Fig. 1.

40 Fig. 7 is a perspective view of the free end portion of the shaft portion of the device.

Fig. 8 is a perspective view of the point member employed and

45 Fig. 9 is an elevational view of a modified form of construction partially broken away.

50 My device being adapted for making circular cuts in tin bodies, the same broadly consists of a tubular shaft 10 fixed to the end of an operating handle 11 and provided with an adjustable centering point 12 upon its free end with metal cutters 13 and 14 upon the opposite sides of the shaft and one

of which cutters is adjustable relatively to the said point. 55

The shaft 10 is arranged with a screw 15 axially journaled therein with its inner end connected by means of a swivel 16 with the inner end or head 17 of the shaft, which head is attached to the handle 11 by rivets 18. 60

A longitudinal side slot 19 is provided in the shaft 10 at the side thereof opposite the cutter or blade 13 and the point 12 has an attaching sleeve 20 through which the screw 15 is journaled, opposite projecting lugs 21 65 and 22 being carried by the sleeve 20 for seating within the adjacent end of the slot 19 and an oppositely arranged notch 23 provided in the end of the shaft 10.

A lock nut 24 is threaded upon the screw 70 15 outwardly of the sleeve 20 for locking the parts together preventing the screw 15 from rotating during the operation of the device. The movable cutter or blade 14 is provided with a collar 25 slidably arranged within the 75 shaft 10 and threaded upon the screw 15 for longitudinal movement during the turning of the screw by means of a handle 26 carried by the outer free end of the screw.

The cutter 14 is shaped substantially like 80 an arrow head having a neck 27 slidably arranged within the slot 19. During the operation of the device, the point 12 and cutter 13 may be employed for cutting a circle of a radius equal to the distance between the point 12 and the cutter 13, the point 12 being punched through the work such as tin and a handle 11 employed for revolving the shaft 10 around the point 12 85 as a center with the cutter 13 cutting 90 through the tin.

When it is desired to cut a circle having a radius of a different length from that just described, the nut 24 is turned and moved outwardly upon the screw 15, releasing the 95 sleeve 20 and permitting the point 12 to be reversed in its position to that illustrated by dotted lines in Fig. 1 of the drawing. The point 12 will then be in a position for co-operating with the adjustable cutter 14 100 which cutter is adjusted for cutting a circle of the desired diameter by moving the screw 15 by means of its handle 26 for feeding the cutter 14 longitudinally of the shaft 10. When the cutter 14 is properly positioned, 105 the nut 24 is tightened upon the sleeve 20

and the device is ready for use in the manner heretofore explained and a circular cut readily made in the sheet metal being operated upon.

5 My device is serviceable as a can opener and by reason of its adjustable features may be employed upon different sized cans and provides in a single implement for operations which would usually employ a plurality of different sized openers.

10 In the modified form of the invention shown in Fig. 9, a shaft 10' is provided fixed upon a handle 11' and having rigid cutters 13' and 14' projecting from opposite sides of the shaft. A point member 12' is carried by a threaded terminal portion 15' of the shaft 10' for positioning at either side of the shaft for employment with either of the 15 said cutters while lock nuts 24' are carried by the terminal portion 15' for locking the point member 12' in either of its opposite positions. The operation of this form of the device will be apparent, the cutters being serviceable selectively with the point member 12' when positioned upon the side 20 of the shaft 10' adjacent such cutter.

What I claim as new is:—

1. A can opener including a shaft, a handle rigid with the shaft, a centering point adjacent the free end of the shaft reversible in position from one side to the other side of the shaft, and cutters carried by the shaft at the opposite sides thereof upon which the point is positionable, said

cutters being at different distances from said 35 point, substantially as and for the purpose described.

2. A can opener comprising a shaft, a handle rigid with the shaft, a centering point adjacent the free end of the shaft reversible in position from one side to the other side of the shaft, and a fixed and an adjustable cutter carried by the shaft at the opposite sides thereof upon which the point is positionable, substantially as and for the 40 45 purpose described.

3. A can opener comprising a handle, a tubular shaft having a head fixedly secured to one end of the handle, a screw axially arranged within the shaft and having an 40 unthreaded portion, a swivel connection between said head and said screw, an operating handle upon the free end of the screw 50 outwardly of the shaft, said shaft having a longitudinal slot in one side thereof, a cutter member having a collar threaded upon the screw and a cutting head projecting through said slot outwardly of the shaft, a centering point member freely mounted upon the unthreaded portion of said screw 55 adjacent the free end of the shaft and having a lug positioned within said longitudinal slot, and means on the screw to retain said point member with its said lug in said slot, substantially as and for the purpose described.

In testimony whereof I affix my signature.
LOUIS JAKUBEC.
